PLANE.

1,074,821.

Specification of Letters Patent.

Patented Oct. 7, 1913.

Application filed August 21, 1912. Serial No. 716,246.

To all whom it may concern:

Be it known that I, FRANK D. STINE, a citizen of the United States, residing at Kansas City, in the county of Jackson and 5 State of Missouri, have invented certain new and useful Improvements in Planes; and I do declare the following to be a full, clear, and exact description of the invention, such as will enable others skilled in the art to 10 which it appertains to make and use the same, reference being had to the accompanying drawings, and to the letters and figures of reference marked thereon, which form a part of this specification.

15 My invention relates to planes, and more particularly to a class known as a rabbet plane, the principal object of the invention being to provide a plane of that type having a bit adapted for quick removal or adjustment on the body of the tool, and adjustable knives for marking a path in front of the bit.

20 A further object of the invention is to provide the tool with an adjustable guide member whereby it may be held in vertical 25 position when moved over a flat surface.

25 A further object of the invention is to provide the new and improved details of structure hereinafter described, claimed, and 30 illustrated in the accompanying drawings, wherein:—

35 Figure I is a perspective view of a plane constructed in accordance with my invention, showing its application to a flat surface, and co-operation with a temporary guide strip which is located adjacent the guide member. Fig. II is an elevational view of the opposite side of the plane.

40 Fig. III is a vertical sectional view on the line III—III, Fig. I. Fig. IV is a sectional view on the line IV—IV, Fig. II. Fig. V is a perspective view of one of the side cutting blades and its mountings. Fig. VI is a detail view of the clamping device.

45 Referring more in detail to the parts:— 1 designates the body of the plane which is provided with a rear handle 2 and a forward knob 3, and whose lower edge 4 is finished to a uniform thickness, the height 50 of the finished portion being the total depth the plane can cut.

55 Projecting from the inner surface of the body and inclined downwardly and forwardly toward the front is a shelf 5, having a bowed upper surface, the lower end

of which lies adjacent a slot 6, which extends through the body in front of and parallel with the shelf 5.

Adjustably secured to the upper surface of shelf 5, by a screw 7, is a bit 8, comprising a plate portion 9, one edge of which is adapted to project through the slot 6 and lie flush with the opposite surface of the plane, the other edge being projected laterally from the inner face of the plane to a 60 desired width, the width of the cut being determined by the width of the particular bit selected, each, however, having a slot 10 extending longitudinally near its center and provided with a laterally opening mouth 65 10' which opens from the inner side of the bit so that the screw 7 may enter the groove from the side.

70 Revolubly mounted in shelf 5 is a shaft 11, having a gear wheel 12 rigidly secured 75 on its upper end, which meshes with teeth 13 on the underside of the bit, the opposite end of the shaft being provided with a thumb nut 14, which is accessible from the outside of the plane.

80 Projecting laterally from the body 1, above the gear wheel 12 and bit 8, is a boss 15, and threaded through said boss is a thumb screw 16, which is adapted to bear on the top of bit 8 and spring same over the 85 bowed surface of shelf 5, to clamp the bit beneath screw 7 and hold it rigidly in place.

85 It is apparent that by slightly loosening screw 16 teeth 13 will be lifted slightly from gear 12, and to free the bit 8, so that 90 by turning the thumb nut 14 it may be raised and lowered to regulate the depth of the cut.

95 Slidably mounted in a vertical, dove-tailed groove 17 near the forward end of body 1 is a knife 18, having a vertical slot 18' through which a screw 19 is projected into said body for holding the knife in adjustable position.

100 Mounted on pins 20 which are slidably mounted in apertures in the plane body, and extending parallel with the face of the plane opposite the knife 18, is a bracket 21, having rigid bosses 22 and an adjustable screw 22' on the inner face, the beveled inner faces of which form a dove-tailed channel for holding a knife 23, which is held in place when set by tightening the screw head against the edge of the knife.

110 A set screw 24 is located in the upper

edge of the plane body and adapted for engaging one of the pins 20 to hold the bracket in set position.

Slidably mounted in the plane body and 5 projecting laterally therefrom are rods 25, having downturned ends 26 projected into sockets 27 in a guide bar 28 and pivotally connected therewith by pins 29, the rods being held frictionally in an adjusted position 10 by the set screws 30 which extend through the top of the plane body and impinge thereagainst.

The bar 28 is adapted to travel along the 15 surface upon which the plane is working and against a guide strip 32 which may be nailed to the surface.

On the outside of the plane is a depth gage 33 having a slotted shank 34 adapted for engagement by a thumb nut 35 in such a 20 manner that the gage may be set and secured for any depth.

In use, a bit is placed on shelf 5, so that 25 screw 7 enters slot 10 through the laterally opening mouth 10' and is moved upwardly and laid closely against the body of the plane. The screw 16 is then slightly lowered, and the thumb nut 14 turned to adjust the cutting edge to the proper depth, at which point the screw 16 is turned to its 30 limit to tighten the bit in place. The knife 18 is always in line with the outside cutting edge, but the knife 23 may be adjusted laterally and secured in line with the inside cutting edge, so that when the plane is moved 35 forwardly the auxiliary knives will mark the path of the chisel knife.

If it is desired to cut a rabbet, the guide 40 28 is lowered to the limit of its pivotal mounting, and firmly set by set screws 30 so that the inside edge thereof may move along the edge of the board, while the bit cuts its way downwardly, and the knives 18 and 23 are clearing the corners of the slot.

When it is desired to cut a mortise for 45 stair work or the like, a strip 32 is temporarily nailed to the board the guide 28 spaced a desired distance from the body of the plane, and the set screws 30 tensioned so as to exert frictional resistance on rods 25.

50 As the plane cuts into the piece, the operator presses downwardly on the plane body to lower same relative to the rods 25 and the guide bar, the rods slipping over the set screws to allow the plane body to lower. 55 With this arrangement the plane may be guided along a flat surface and cut a vertical groove.

It is readily apparent that a bit may be quickly and easily inserted without loosen-

ing or tightening the screw 7, as the surface 60 of the shelf 5 allows the bit to be sprung so as to clamp tightly beneath the head thereof.

Having thus described my invention, what I claim as new therein and desire to secure by Letters-Patent, is:—

1. A rabbet plane comprising a body portion having a laterally projecting shelf provided with a curved upper surface, means at upper and lower positions on the shelf for binding a bit, and a bit adapted for application to the shelf and engagement by the binding means, for the purpose set forth.

2. A rabbet plane comprising a body member having a laterally directed and longitudinally curved shelf, a keeper at one end 75 of the shelf, a tooth member near the opposite end of the shelf, a bit adapted to overlie the shelf and having an opening for receiving said keeper and having a rack face adapted for engaging the tooth member, a 80 boss on the body portion overlying the shelf, and a set-screw on said boss adapted for engaging the bit binding the same to said curved shelf and moving the rack portion thereof against the tooth member, substantially as set forth.

3. In a rabbet plane, a body member having a laterally directed and longitudinally curved shelf, a stud on said shelf, a bit having a longitudinal slot adapted to receive 90 said stud, and means on the body of the plane for engaging said bit and binding same to the curved shelf.

4. In a rabbet plane, a body member having a laterally directed and longitudinally curved shelf, a retaining member on said shelf, a bit having a laterally opening slot adapted for receiving said retaining member, and means on the body of the plane for engaging said bit and binding the same to the curved surface of said shelf and thereby against the retaining member.

5. In a rabbet plane, a body member having a laterally directed and longitudinally curved shelf, a retaining member near one 105 end of said shelf, a bit having a laterally opening slot adapted for receiving said retaining member, and means on the body of the plane for engaging said bit and binding the same to the curved shelf and thereby 110 against the retaining member.

In testimony whereof I affix my signature in presence of two witnesses.

FRANK D. STINE.
